UNITED STATES PATENT OFFICE.

T. LANGDON AND C. WEITMAN, OF HAZLETON, IOWA.

BROOM.

Specification of Letters Patent No. 29,179, dated July 17, 1860.

To all whom it may concern:

Be it known that we, THOMAS LANGDON and CHRISTIAN WEITMAN, of Hazleton, in the county of Buchanan and State of Iowa, 5 have invented a new and useful Improvement in the Construction of Brooms; and we do hereby declare that the following is a full, clear, and exact description of the same, reference being had to the accompanying 10 drawings, making a part of this specification, in which—

Figure 1 represents a broom constructed upon our improved plan. Fig. 2 is a transverse section taken through the broom of 15 Fig. 1.

Similar letters of reference indicate corresponding parts in both figures.

This invention is an improvement in constructing brooms of broom-corn, splints, or 20 other suitable articles, without using thread or wire to hold the parts together as in the common practice at the present time. The brooms made upon our plan will be more durable, hold together longer less expensive 25 and neater in appearance and more desirable in every respect than the cord or wire wrapped brooms. But the most important feature of our invention is that the same fixtures may be continually used, as often as 30 the old broom is worn out. This is done by simply unscrewing the handle and loosening the screws of the T piece, when changing the broom corn or other material and tightening the whole again. Our invention for 35 this purpose does not consist in the employment of clamping plates and screws nor caps and screws and nails, broadly but, it consists in the use of a screw iron of a T-shaped metal cap for the ends of the wisps 40 of broom corn two clamping plates between which the T iron is interposed, and a handle that secures the whole together in the manner hereinafter described and represented.

To enable those skilled in the art to fully 45 understand our invention we will proceed to describe its construction and operation.

In the drawing A, represents a broom handle having on its end a nut α .

B, is a flattened conical cap, which has a hole through its end, and the cap may be 50 made of sheet iron or brass or any suitable metal.

C, is a screw rod that is set into the handle A, which rod has a T-piece B', secured on its end as shown in dotted lines Fig. 1, with 55 poles punched through it to receive the screws d, d .

D, D, are two flat plates having holes punched through them near each end,—these plates are of the same length, and their ends 60 are curved abruptly over.

Now with these parts the broom is put together in the following manner: The T-piece B', is laid between the two plates D, D, the four screws d, d, d, d , are passed through 65 them, uniting them at the extremity of the screws, the spaces between are then filled with the broom material and the screws tightened, the ends of the wisps are then inserted in the cap and the handle screwed 70 on, thus confining the bundle in a flattened shape similar to ordinary brooms. The short ends of the broom - corn are now brought compactly together and the conical cap slipped over them in a neat manner the 75 screw rod C, passing through the hole in the heads of the cone, the handle is now screwed on to the rod C, and the whole is bound tightly together. The ends of the broom are then trimmed which completes the article for 80 the market.

Having thus described our invention what we claim as new and desire to secure by Letters Patent is—

The combination of the T piece B', its rod 85 C, clamping plates D, D, cap B, nut α , with the handle A, all relatively arranged in the manner herein set forth.

THOMAS LANGDON.
CHRISTIAN WEITMAN.
